JOSEPH C. SEIDLER, OF WHEELING, WEST VIRGINIA

MEANS FOR COVERING CLEANED GARMENTS

Application filed August 2, 1929. Serial No. 382,911.

This invention relates to garment applying apparatus designed primarily for use in cleaning and pressing shops and in garment manufacturing plants.

5 The primary object of the invention is to provide an apparatus which enables the garment, following cleaning or pressing, to be easily and quickly placed into a cover, such as a paper bag, so as to protect said garment prior to delivery to the customer.

10 The present practice is to insert the garment into the bag or cover through the open bottom of the latter, the garment being held in one hand and the bag in the other, but 15 with this practice the garments frequently come into contact with the floor or other objects and become soiled. The present invention aims to provide an apparatus which 20 enables the cover to be applied to the garment without any possible soiling thereof as in 25 the present practice.

The invention further aims to provide an apparatus of this type which is of simple and compact construction, occupying a small 25 amount of space and which enables the cover to be easily and quickly applied.

In describing the invention in detail, reference is herein had to the accompanying drawings, in which—

30 Fig. 1 is a side elevation of the invention partly broken away;

Fig. 2 is a similar view of a modified form of the invention, partly broken away and in section; and—

35 Fig. 3 is a front elevation of Fig. 2, also partly broken away and in section.

In the form of the invention shown in Fig. 1, a vertical standard 1 is employed to the bottom of which is attached a base flange 2 adapted to rest on the floor of the shop, a lateral arm 3 being attached at the opposite end or top of the standard. Secured to and depending from the outer end of the arm 3 is a tube 4, said tube having its lower 40 end terminating at a distance above the level of the base flange 2. Said tube 4 is provided with a longitudinal slot 5 extending throughout the major portion of its length, a cap 6 being secured to the lower end of said tube and carrying a hook 7.

45 end terminating at a distance above the level of the base flange 2. Said tube 4 is provided with a longitudinal slot 5 extending throughout the major portion of its length, a cap 6 being secured to the lower end of said tube and carrying a hook 7.

Vertically slidable interiorly of the tube 4 is a cylindrical member 8 carrying a hook 9, said hook 9 projecting outwardly through the slot 5. Adjacent the upper end of the tube is journaled a pulley 10, over which 55 is trained a cord 11, one end of said cord being secured to the cylindrical member 8, while its opposite end is disposed exteriorly of the tube and has a hand grip 12 secured thereto. The member 8 possesses such 60 weight that it normally occupies its fully lowered position and will return by gravity to such position following release of the pull cord 11 employed for elevating it.

65 In operation, a top of a garment cover C, here shown in the form of a bag open at its bottom, is engaged over the hook 9, as shown at E, following which the end of the cord having the hand grip 12 is pulled downwardly, thereby raising the member 8 and 70 thereby-carried bag to the full line position shown in Fig. 1. The garment G, arranged on the usual hanger H, is then suspended from the hook 7, following which the cord is released and the cover C moved downwardly to enclose the garment, as shown in dotted lines in Fig. 1, the garment being received through the open bottom of the bag. The hook of said hanger is then disengaged 75 from the hook 7, whereupon the garment is 80 ready for delivery to the customer.

In the modified form of the invention shown in Figs. 2 and 3, the upper end of the tube 4 is closed by means of a cap 13 having an eye 14 therein. Said eye 14 is provided 85 in order that the tube may be suspended from the ceiling, as by means of a hook in the ceiling. This modified form of the invention is distinguished from that shown in Fig. 1 in that the latter can be moved about the 90 shop as desired, the base being weighted to sustain the standard upright. Or, the base 2 may be permanently secured to the floor, as by means of screws.

95 In both forms of the invention it will be noted that the cleaned or pressed garment is supported in a fixed position so that in lowering the base thereover the hands of the operator need not touch the garment, thereby preventing soiling.

What is claimed is—

A garment-cover applying apparatus comprising a vertically depending stationarily supported tube having therein a longitudinally extending slot, a cap fixed on the lower end of said tube and closing the lower end of said slot, a hook attached to said cap for supporting a garment hanger, a member vertically shiftable within and adapted normally to occupy lowered position with respect to said tube, a cover support carried by said member, said support being projected outwardly through and movable along said slot in vertical shifting movements of said member, a pulley in the upper end of said tube, and a pull-cord trained over said pulley, one end of said cord being attached to said shiftable member and the other end being disposed exteriorly of the tube and affording means whereby said member may be elevated and lowered relative to the garment supporting hook, and moving a cover borne by said support out of and into enclosing relation to a garment suspended from said hook.

In testimony whereof, I affix my signature.
JOSEPH C. SEIDLER.
